[57] CLAIM

The ornamental design for credit/debit authorization and financial transaction terminal or similar article, as shown and described.

DESCRIPTION

FIG. 1 a top, front perspective view of a credit/debit

authorization and financial transaction terminal or similar article showing our new design;

FIG. 2 is a left end elevational view thereof;

FIG. 3 is a rear elevational view thereof;

FIGS. 5 and 6 are a top, front perspective view and a rear elevational view respectively thereof, omitting all

illustrative broken lines for clarity of disclosure;

FIG. 7 is a top, front perspective view of a second embodiment of our new design;

FIG. 8 is a left end elevational view thereof;

FIG. 9 is a rear elevational view thereof;

FIG. 10 is a right end elevational view thereof;

FIGS. 11 and 12 are a top, front perspective view and a rear elevational view respectively thereof, omitting all

illustrative broken lines for clarity of disclosure;

FIG. 13 is top, front perspective view of a third embodiment of our new design;

FIG. 14 is a left end elevational view thereof;

FIG. 15 is a rear elevational view thereof;

FIG. 16 is a right end elevational view thereof;

FIGS. 17 and 18 are a top, front perspective view and a rear elevational view respectively thereof, omitting all

illustrative broken lines for clarity of disclosure;

FIG. 19 is a top, front perspective view of a fourth embodiment of our new design;

FIG. 20 is a left end elevational view thereof;

FIG. 21 is a rear elevational view thereof;

FIG. 22 is a right end elevational view thereof; and

FIGS. 23 and 24 are a top, front perspective view and a rear elevational view respectively thereof, omitting all

illustrative broken lines for clarity of disclosure.

The card imprinter structure is shown in broken lines for illustrative purposes only and forms no part of the claimed design.
